UNITED STATES PATENT OFFICE.

WILLIAM F. NAGEL, OF ENSLEY, ALABAMA.

APPARATUS FOR TREATING TOBACCO.

Application filed April 22, 1925. Serial No. 25,125.

My invention relates to the art of treating tobacco to remove in whole or in part the nicotine and other substances sufficiently volatile, and the object of the present invention is to provide a novel, efficient and easily operated apparatus particularly adapted for the purpose and capable of being made up in small capacity units so that one may treat his own supply of smoking tobacco as needed, removing more or less of the nicotine content as desired.

In the drawing Fig. 1 is a partly sectional view of my apparatus, in a convenient desk or table arrangement.

In Fig. 1 1 is a vessel, preferably cylindrical as shown, with part of its side wall in section at 2. From the upper part of vessel 1 is suspended or held a perforate or fenestrated container 3, 3, preferably a wire cloth basket with relatively open mesh. The tobacco is held in this basket. 4 is a cover with handle or knob 5 and a plurality of ventilating openings as 6, 6, are provided to permit escape of vapors, etc. To insure necessary warmth and adequate saturation of air I provide a tank or container as at 7, the side wall being shown as cylindrical and the inner wall 8 (both shown in section) being substantially part of a cone. Water is held as at 9. The inner surface of wall 8 forms a substantially conical reflector for an electric lamp 10, the flexible leads of which are indicated at 11, and suitable gaps, 12, 12, 12, etc., in the base permit entry of air through openings 13. Here the lamp 10 not only supplies light, which can reach the tobacco through the meshes of basket 3, but also heats the interior so that water

vaporizes from the supply at 9 and maintains the requisite degree of saturation. By 40 convection, as is obvious, the air is constantly renewed, ingress being from below and egress through the orifices in the top. The apparatus is very simple and well adapted for use by the smoker himself as it has only 45 to be connected to a light socket by suitable cord conductors, when, with adequate supply of water in the reservoir, it is ready to operate.

The effect of the sustained heat, together 50 with the exposure to intense light, causes the more volatile contents of the tobacco to come off into the water-saturated or moist air and thus to be carried off through the outlets at top. It is obvious that the process 55 may be continued as long as desirable.

If the basket 3 is deep enough the same apparatus may be used to treat cigars, the time required, however, being related to the degree of access of the warm atmosphere to 60 the interior of the cigar.

Having described my invention, what I claim is:—

In apparatus of the class described, a chamber, a fenestrated container in the upper part of said chamber arranged to hold tobacco, an incandescent lamp beneath said container, and a second container arranged to hold liquid and having one of its walls arranged as a reflector for said lamp, substantially as shown.

In witness whereof I have hereunto set my hand at Montgomery, Alabama, this March 19th, 1925.

WILLIAM F. NAGEL.
